DESIGN FOR A DOLL OR SIMILAR ARTICLE

Zinaïda Harpignies, Kew Gardens, N. Y.

Application December 9, 1943, Serial No. 111,972

Term of patent 3½ years

To all whom it may concern:

Be it known that I, Zinaïda Harpignies, a citizen of Belgium, residing at 84-09 Talbot Street, Kew Gardens, in the county of Queens and State of New York, have invented a new, original, and ornamental Design for a Doll or Similar Article, of which the following is a specification, reference being had to the accompanying drawing, forming part thereof.

In the drawing

Fig. 1 is a front view of a doll or similar article, showing my new design;

Fig. 2 is a back view of the doll shown in Fig. 1; and

Fig. 3 is a side view of the doll shown in Fig. 1.

I claim:

The ornamental design for a doll or similar article, as shown.

ZINAÏDA HARPIGNIES.
